DIE

Christian A. Cadenbach, St. Louis, Mo., assignor
to Independent Die & Supply Company, St.
Louis, Mo., a corporation of Missouri

Application November 16, 1935, Serial No. 50,245

13 Claims. (Cl. 164—93)

This invention relates generally to dies and particularly to dies such as are used in the manufacture of shoes for perforating the shoe parts.

The object of the present invention, generally stated, is to provide a die of the character referred to wherein the cutting elements may be removed and replaced with facility by an unskilled operative and without the use of tools.

A further object of this invention is to provide a die construction in which the cutting element is held in position on a base by a stripper plate.

Other objects will become apparent to those skilled in the art when the following description is read in connection with the accompanying drawing, in which:

Figure 1 is a plan view of a die constructed in accordance with the present invention.

Figure 2 is a plan view of the die of Figure 1 with a stripper plate thereof removed.

Figure 3 is a sectional view taken along line 3—3 of Figure 1.

Figure 4 is a view corresponding to Figure 2 but showing a different cutting element.

Figure 5 is a detail sectional view taken along line 5—5 of Figure 2.

Figure 6 is a detail view of the cutting element holding device employed in accordance with the present invention.

In accordance with the present invention a die is constructed and arranged so as to have the cutting parts thereof readily removable from those parts which are usable throughout the life of the die. This permits the cutting parts to be removed and replaced so as to accommodate cutting parts of different designs and thus render such parts as the base and stripper plate adaptable for various operations. In accordance with the present invention the cutting parts are so connected to the base that they may be readily removed and substituted by an unskilled operative and without requiring the use of tools. Likewise the stripper plate may, if desired, be removed and substituted without the use of tools. Although the device of the present invention is, as above stated, readily demountable by an unskilled operative, the device is so constructed and arranged that, except at such times that it is deliberately disassembled, the device is sufficiently rugged and secure to withstand ordinary usage and abuses without liability to accidental disassembly.

Referring now to the drawing for one illustrative embodiment of the invention the device may comprise a base 1 upon which is mounted cutting element 2 which in the embodiment illustrated is composed of a plurality of cutting tubes 3 having

their upper edges sharpened so as to penetrate the leather or other materials to be operated upon. A stripper plate 4 is also employed and in the embodiment provided with a series of apertures 5, one for each of the cutting tubes 3.

In accordance with the present invention the cutting element 2 may be mounted upon base 1 as through an intermediate sub-base 6 and maintained against lateral or sidewise displacement thereon by holding device or plug 7 which will be described in detail hereinafter. In the cutting element 2 is an aperture 8 arranged to be aligned with a corresponding aperture 9 in the base 1 and sub-base 6 to accommodate the plug 7. Supplementing the plug 7 may be any number of pins 10 mounted either in the cutting device 2 or the sub-base 6 and arranged to cooperate with an aperture in the other element.

While the pins 10 actively maintain the cutting element 2 against sidewise displacement relative to base 1 they do not act to prevent actual removal of the cutting element from the base. Removal of the cutting element from the base is prevented through the medium of stripper plate 4 acting through plug 7.

In the embodiment illustrated in the drawings the stripper plate 4 is resiliently mounted upon base 1 by means of a plurality of supports 11, 12, 13 and 14, which may be composed of telescoping members 15 and 16 encircled by a coil spring 17, as shown clearly in Figure 5. Member 15 may, as shown in the drawing, be provided with a headed part 18 for holding stripper plate 4 in position thereon. Stripper plate 4 may then be provided with a plurality of key slots 19, 20, 21 and 22, one for each of the supports 11, 12, 13 and 14. The key slots 19, 20, 21, and 22 are provided with an enlarged end portion 23 of a diameter sufficient to take over head 18, whereas at their opposite ends they are narrowed down to an extent such that when the head 18 is in position therein the stripper plate can not be lifted off.

Suitable means may be provided for moving stripper plate 4 and locking the same in position on supports 11, 12, 13 and 14. One suitable means for accomplishing this result is shown in Figure 1 and may comprise a lever 24 suitably pivoted as at 25 to the stripper plate and having a curved end portion 26 for cooperating with the adjacent support 12. The curved end portion may be so arranged that upon movement of lever 24 to the broken line position, illustrated in Figure 1, the head portion 18 of support 12 will be moved out of the narrow end of slot 20 into the large end thereof, thus effecting a rotation of the stripper

plate about support 14 as an axis and moving the stripper plate into the broken line position shown in Figure 1. When this is done the headed portion 18 of each of the supports 11, 12 and 13 is moved into the enlarged portion of the corresponding key slot and these three slots may then be unseated from the respective heads so that the shield may then be moved to the left so as to bring the head of support 14 into the enlarged portion of slot 22. When it is desired to replace the stripper plate, the operations are carried out in the reversed order—namely, slot 22 is first placed upon the head of support 14 and moved into the narrow end thereof, then the other slots are placed upon their corresponding supports and lever 24 moved back into the position shown in dotted lines in Figure 1, during which movement end 26 cooperates with support 12 to rotate stripper plate 4 in a counterclockwise direction around support 14 as an axis.

In order to lock lever 24 in this position a hole 27 may be provided in stripper plate 4 and a lug 28 provided on lever 24 so that when in full line position the lug 28 will be seated in hole 27 and thus prevent accidental movement of lever 24. It will be understood, of course, that lever 24 has sufficient spring to permit it to be flexed for withdrawal of lug 28 from hole 27. With the arrangement shown in the drawing where the slots 19, 20, 21 and 22 extend in different directions, that is to say, where the enlarged ends of the slots are not on the same side of the narrow ends, it is apparent that the stripper plate cannot be removed by simple translation but only by the particular movement above described. This further prevents accidental removal of the stripper plate.

In order to hold the cutting element 2 down on base 1 or sub-base 6, the holding device or plug 7 may be arranged so as to bear against the underside of stripper plate 4 and thus prevent removal of plug 7 when the stripper plate is in position. Since, however, when the punching operation is performed the stripper plate moves downwardly over the ends of tubes 3 against the action of spring 17 a similar yieldable arrangement is provided in plug 7. In order to accomplish this plug 7 may be composed of a barrel 29 within which is mounted a pin 30, the head 31 of which bears against the underside of stripper plate 4. Barrel 29 may be provided with a shoulder 32 arranged to seat in a recess in cutting device 2 and a spring 33 may be interposed between shoulder 34 in barrel 29 and head 31 so as to bias these parts apart. Thus when the stripper plate is in its uppermost position, shown in the drawing, shoulder 32 is seated in position holding barrel 29 in holes 8 and 9 so as to prevent sidewise displacement while at the same time the action of the shoulder 32 through spring 33 holds the cutting device 2 down against the sub-base 6, but, nevertheless, permits stripper plate 4 to move against the action of springs 17 and 33.

The cutting device 2 may, as particularly shown in Figure 2 be composed of a plurality of parts so that the same die may be used on large shoes and small shoes. In order to accomplish this an extra die section 42 may be provided having a series of cutting tubes 43 constituting an extension of the design formed by tubes 3. The section 42 may, therefore, be removed from the device without molesting the main portion thereof 2 and the same stripper plate may be used whether the section 42 is employed or not.

As particularly shown in Figure 4 the sectional

cutting device may also be arranged so as to form different designs. In the embodiment illustrated in Figure 4 a main sectional part 52 is provided with a series of tubes 53 which may be understood as forming the basic design. Any number of auxiliary sections, such as 62, having a series of tubes 63 arranged in the desired manner to complete the design formed by tubes 53 may then be employed supplementing section 52. In either case the respective cutting sections may be held in the position, as hereinbefore described in accordance with the present invention.

From the foregoing description it is apparent that the invention accomplishes its objects and since the operation thereof will be clear from the foregoing description further reference to the operation of the device is deemed unnecessary.

Since it is apparent that the illustrative embodiments hereinbefore described are susceptible of many modifications without departing from the spirit of this invention, it is to be distinctly understood that the invention is not limited to the embodiments hereinbefore disclosed in detail but that such modifications and the use of such individual features and sub-combinations of features as do not depart from the spirit of this invention are, although not specifically described herein, contemplated by and within the scope of the appended claims.

Having thus described the invention, what is claimed is:

1. A device of the kind described, comprising, a base, a die element fitting on said base, means for preventing sidewise displacement between said die and base, and a stripper plate carried by said base overlying said die element and biasing the same against the base.

2. A device of the kind described, comprising, a base, a die element fitting on said base, said base and die element having cooperating apertures, plugs fitting in said apertures and freely liftable from the apertures in both said members, and means for holding said plugs against removal.

3. A device of the kind described, comprising, a base, a die element fitting on said base, said base and die element having cooperating apertures, plugs fitting in said apertures and freely liftable therefrom, said plugs having a resilient part, and a shield carried by said base and bearing against the resilient part of said pins.

4. A device of the kind described, comprising, a base, a die element fitting on said base, said base and die element having cooperating apertures, plugs fitting in said apertures and freely liftable therefrom, said plugs having a resilient part, and a shield resiliently mounted on said base for movement against the action of the resilient part of said pins.

5. A device of the kind described, comprising, a base, yieldable supports on said base, a shield carried by said supports, a die interposed between said shield and said base, and yieldable means bearing against said shield for biasing said die against said base.

6. A device of the kind described, comprising, a base, yieldable supports on said base, a shield having a series of key slots for cooperating respectively with said supports, and means on said shield for moving the shield relative to the base to seat the supports in said key slots.

7. A device of the kind described, comprising, a base, yieldable supports on said base, a shield having a series of key slots arranged in non-parallel relation, said key slots cooperating with

the respective supports, and means for rotating said shield about one of said supports to seat and unseat the other supports in their respective key slots.

- 5 8. A device of the kind described, comprising, a base, a plurality of yieldable headed supports on said base, a shield having a series of slots for cooperating one with each of said supports, said slots having an enlarged portion at one end to take over the heads of said supports, said slots arranged so that the enlarged portions of all but one of said slots extend in the same 10 rotational direction with reference to said one slot, and a lever mounted on said shield and cooperating with one of said supports for rotating said shield about said one slot.
- 15 9. A device of the kind described, comprising, a base, a plurality of yieldable headed supports on said base, a shield having a series of slots for cooperating one with each other of said supports, said slots having an enlarged portion at one end to take over the heads of said supports, said slots arranged so that the enlarged portions of all but one of said slots extend in the same 20 rotational direction with reference to said one slot, a lever mounted on said shield and cooperating with one of said supports for rotating said shield about said one slot, and means for locking said lever in the position whereat 25 the heads of the supports are removed from said 30 enlarged portion of the slots.

10. A device of the kind described, comprising, a base, a sectional die element fitting on said base, said base and each of said die sections having cooperating, apertures, plugs fitting in said apertures, and a stripper plate arranged to hold said plugs against removal. 5

11. A device of the kind described, comprising, a base, a sectional die element fitting on said base, said base and each of said die sections having cooperating, apertures, plugs fitting in said apertures, said plugs having a resilient part, and a resiliently mounted shield carried by said base and movable against the action of the resilient parts of said plugs. 10

12. A device of the kind described, comprising, a base, a die element fitting on said base, said base and die element having cooperating apertures, plugs fitting in said apertures and freely removable therefrom, and a shield extending over said plugs and constituting the only 20 means for retaining the same against removal. 25

13. A device of the kind described, comprising, a base, a die element fitting on said base, said base and die element having cooperating apertures, plugs fitting in said apertures, a shield 30 extending over said plugs in spaced relation to the die element, each of said plugs having a part engaging the die element and a part engaging the shield, said parts being yieldable relative to each other.
